UNITED STATES PATENT OFFICE

151,109

DESIGN FOR A MILITARY BRUSH

Franz Wagner, Chicago, Ill., assignor, by mesne assignments, to Owens-Illinois Glass Company, Toledo, Ohio, a corporation of Ohio

Application October 14, 1946, Serial No. 133,949

Term of patent 3½ years

(Cl. D86—10)

To all whom it may concern:

Be it known that I, Franz Wagner, a citizen of the United States of America, residing at Chicago, in the county of Cook and State of Illinois, have invented a new, original, and ornamental Design for a Military Brush, of which the following is a specification, reference being had therein to the accompanying drawings, forming a part thereof, wherein:

Fig. 1 is a perspective view of a brush showing my new design, and with the bristles omitted for convenience in illustration;

Fig. 2 is a side elevation; and

Fig. 3 is an end elevational view thereof.

The essential feature of my design resides in the portions shown in full lines.

I claim:

The ornamental design for a military brush, substantially as shown and described.

FRANZ WAGNER.
